United States Patent Office

Des. 211,972
Patented Aug. 13, 1968

211,972

DISPLAY STAND FOR DISHES AND THE LIKE

Eirvan C. Cantrell, 1801 W. Anaheim St.,
Long Beach, Calif. 90813

Filed Apr. 24, 1967, Ser. No. 6,789

Term of patent 14 years

(Cl. D80—9)

FIG.1

I claim:

The ornamental design for a display stand for dishes and the like, as shown and described.
